UNITED STATES PATENT OFFICE.

JOSEPH ALBERT SEVIGNY, OF NEW BEDFORD, MASSACHUSETTS, ASSIGNOR TO JAMES H. MARTIN, OF FALL RIVER, MASSACHUSETTS.

STOVE.

Application filed August 28, 1922. Serial No. 584,676.

My invention relates to improvements in cook stoves and more particularly to that class known as combination coal and gas stoves.

5 The object of my invention is to provide an improved combination coal and gas stove equipped with an oven adapted to receive heat from either the coal burning portion of the stove or from the gas burners. A further object of my invention is to provide a 10 stove as mentioned equipped with means for heating water in a boiler for domestic purposes, so arranged that the water will be heated either by the coal burning portion of 15 the stove, by the oven heating burners, or both. A further object of my invention is to provide a stove as mentioned which, in cold weather, when coal is used, will serve as a heating stove for heating the room or a 20 small suite of rooms. A further object of my invention is to provide a stove of the class mentioned which shall be of neat and ornamental appearance. Other objects will appear hereinafter.

25 With these objects in view my invention consists generally in a stove comprising a coal burning portion of the general type known as "base-burners", an oven arranged at the side of the body portion thereof and 30 receiving heat directly therefrom, and a gas burner for heating said oven. My invention further consists in a device as mentioned, in which the stove top comprises two vertically spaced rectangular members, the lower 35 member consisting of a flat plate constituting the top of the oven and extending around the upper end of the body of the base burning portion, and an upper member constituting a grid to receive the ordinary stove 40 lids over the coal burning portion, and the usual spiders over the oven portion, there being gas burners arranged beneath the latter, and a vertical partition between said members spacing the coal burning portion from 45 the gas burning portion. My invention further consists in a device as mentioned in combination with a water coil or jacket surrounding the fire pot of the base-burner, a coil arranged within said oven, a burner arranged 50 beneath said coil, and circulating pipes connecting said coils and affording means for connecting the same to the domestic water boiler. My invention further consists in various details of constructions and 55 arrangements of parts all as will be fully de-

scribed hereinafter and particularly pointed out in the claims.

My invention will be more readily understood by reference to the accompanying drawings forming a part of this specification 60 and in which—

Fig. 1 is a front elevation of a stove embodying my invention in its preferred form,

Fig. 2 is a horizontal section on the line 2—2 of Fig. 1, portions being broken away 65 and one of the lids removed,

Fig. 3 is a horizontal section on the line 3—3 of Fig. 1,

Fig. 4 is a detail vertical section on the line 4—4 of Fig. 2,

Fig. 5 is a detail rear elevation, and

Fig. 6 is a detail section on the line 6—6 of Fig. 2.

Referring now to the drawings, the coal burning portion of the stove comprises a fire 75 pot 1 resting upon an ash box 2 supported by legs 3. These portions are preferably of cast iron. Resting upon the fire pot portion 1 is a body 4, preferably circular in cross-section. These portions of the device are 80 similar to the ordinary base-burner stove. The ash box 2 is provided with the usual draft and clean-out door 5 and the body is provided with the usual door 6. Arranged beside the body 4 is an oven 7 substantially 85 coextensive in height with said body portion and provided with a door 8 which may be supported in any preferred manner, as by hinges 9. The walls of the body portion 4 are unlined and are preferably of sheet iron 90 and the adjacent wall of the oven 7 is bent outwardly as indicated at 10 (see Fig. 3) and attached to the wall 4. It will thus be seen that the portion of the wall 4 of the coal burning portion, between the walls 10 95 forms a portion of the oven wall and the oven will receive heat radiated directly from this section of the wall of the body portion of the coal burning section of the stove. 11, 11 indicate racks for adjustably supporting 100 the oven slide or shelf 12. A gas burner 13 is arranged beneath the oven 7 and a burner 14 is arranged within the upper portion of the oven, affording means for heating the oven by gas. The side of the oven remote 105 from the coal burning portion of the stove is supported by legs 15.

The top of the stove comprises two rectangular, horizontal members 16 and 17, the latter being arranged above the former and 110

2
spaced therefrom by peripheral walls 18, 19 and 20. A vertical wall 21 extends from the front to the back of the top between the members 16 and 17 and spaces the portion 5 over the coal burning section from that over the oven. The member 16 comprises a flat plate constituting the top of the oven and extending around the upper edge of the body 4, said plate having an opening 22 substantially commensurate in diameter with 10 the body 4 and provided with a depending flange 23 fitting within the upper end of said body and to which the same is secured. A flue 24 extends from the back wall 20 and 15 is provided with a damper 25. The upper member 17 constitutes a grid to receive the ordinary stove lids 26 over the coal burning portion, and the spiders 27 over the oven, gas burners 28 being arranged beneath the 20 latter between the members 16 and 17. It is obvious that the arrangement may be such as to provide for any number of plates of spiders, this being dependent entirely upon the size and relative proportions of the several 25 parts.

The fire pot 1 is formed with a water coil or jacket 29 from which extend pipes 30 for connecting the same to a domestic water boiler. Arranged in a housing 31 preferably in the bottom of the oven and over the burner 13 is a water coil 32 which is connected by pipes 33 with the pipes leading from the coil 29. It will thus be seen that the coils 29 and 32 are connected and are provided with means for attaching the same to a domestic water boiler. By this arrangement, the water in the boiler will be heated whenever the oven is heated either by the coal fire or from the gas burner. It will be 40 further noted that when the oven is heated from the coal burning portion, that both coils will be heated. This is of particular advantage as, in winter time, when the most hot water is usually needed, the water will 45 be more rapidly heated, in that both coils will be heated simultaneously.

The stove is provided with a back 34 extending upwardly from the rear portion and provided at the top with warming chambers 50 35 which may or may not be provided with doors. As illustrated in the drawings, I have illustrated one chamber provided with a door 36 and the other chamber without a door. 37 indicates side brackets supporting 55 the chambers which may be of any preferred form.

Arranged beneath one of the openings which is normally closed by one of the front lids 26, I provide a coal chute for directing the coal through the opening 22 and to prevent the same from accumulating between the members 16 and 17. This preferably comprises an inclined, curved sheet metal member 38 supported at its lateral 60 edges by brackets 39. The brackets 39 are

provided with upwardly extending flanges 40 forming sides to the chute. This construction provides a simple device for directing the coal into the stove and preventing the same from accumulating between the members 16 and 17; and at the same time permits heat to circulate freely to uniformly heat the top of the stove between the walls 19 and 21. This construction is clearly shown in Figs. 2 and 6 of the drawings. 70

It is obvious that the stove as above described will be efficient as a coal burning stove for use in winter or as a gas burning stove in warm weather. The construction of the coal burning portion is such that when the same is used in cold weather, it not only serves as a cook stove but is extremely efficient to heating the kitchen or a small suite of rooms. A large portion of the shell of this portion of the stove will radiate heat into the rooms, while an ample portion, that between the walls 10, 10, will afford sufficient heat for heating the oven. Furthermore, the stove is of such a neat and ornamental appearance that it will greatly add to the furnished appearance of the room where used. 75

In regard to the means for heating the water for the domestic boiler, it will be noted that in the summer time, when gas is used, the water may be heated by means of the burner 18. In winter, when more hot water is usually required, both coils will be heated from the coal burning portion. It is obvious that the coils 29 will receive heat directly from the fire in the fire pot; and as the oven is heated from the base-burner portion, and the coil 32 is arranged within the stove, this latter coil will also be heated from the coal burning portion. 80

I claim—

1. In a stove, a coal-burning portion of the base-burner type having a fire pot in which coal is burned and an unlined sheet metal body of the same cross-sectional shape as the fire pot and rising from the walls thereof, a chambered top portion supported on the body portion, and a flue leading from said chamber, whereby the products of combustion from the coal pass up through the body portion and the chamber of the top portion directly to the flue, in combination with an oven arranged beside the unlined sheet metal body and at a higher level than the fire pot, the walls of the oven joining said body on opposite sides thereof and the portion of the unlined wall of the body between the points where the oven wall meets the body constituting a portion of the wall of the oven, whereby when coal is being burned in the base burner the oven is heated solely by transference of heat through said portion of the unlined wall of the body, and gas burners arranged for heating said oven independently of the coal-burning portion. 110

2. In a cook stove, a coal burning portion 120

of the base burner type, an oven arranged beside the same and receiving heat directly therefrom, a gas burner for heating said oven independently of said coal burning portion and a top for said stove comprising a pair of horizontal rectangular members, spaced one above the other, the lowermost member comprising a flat plate constituting the top of the oven and having an opening 10 above and substantially commensurate with the upper end of said coal burning portion, the upper member comprising a grid for the usual stove lids above the coal burning portion and with spiders above oven, and 15 gas burners arranged beneath said spiders, substantially as described.

3. A device as set forth in claim 2 further characterized by walls connecting the upper and lower members of the top and dividing 20 the space between the same over the coal burning portion from that over the oven, substantially as described.

4. In a stove, a coal-burning portion of the base-burner type having a fire pot which 25 has a water coil integral therewith, an un-

lined sheet metal body of the same cross-sectional shape as the fire pot and rising from the walls thereof, a chambered top portion supported on said body and a flue communicating with the chamber of the top portion, whereby the products of combustion from the coal burning in the fire pot pass through the body and chamber of the top portion directly to the flue, in combination with an oven arranged beside the body and 30 at a higher level than the fire pot, a portion of the unlined wall of the body forming a portion of the wall of the oven whereby when coal is being burned the oven will be heated thereby solely by heat transference through 35 said portion of the unlined wall, a water-heating coil in the oven, pipes connecting the water coil in the oven to the water coil on the base-burner, and means for heating the oven and the water coils therein independently of the coal-burning portion.

In testimony whereof I have signed my name to this specification.

JOSEPH ALBERT SEVIGNY.
